(57) **CLAIM**

The ornamental design for a combination air freshener and photo sleeves, as shown and described.

DESCRIPTION

FIG. 1 is a top, front, left side perspective view of a combination air freshener with two photo sleeves and an elastic cord shown in a typical view embodying my design; FIG. 2 is a right side elevational view thereof, the left side elevational view being a mirror image thereof; FIG. 3 is a rear elevational view thereof, the front elevational view being a mirror image thereof; FIG. 4 is a top plan view thereof; and, FIG. 5 is a bottom plan view thereof.
